UNITED STATES PATENT OFFICE

CARL H. LARSON, OF ELKHART, INDIANA, ASSIGNOR TO THE ADLAKE COMPANY, A CORPORATION OF ILLINOIS

ELECTRIC HAND LANTERN

Application filed March 2, 1931. Serial No. 519,429.

This invention relates to electric hand lanterns and has for its object to produce a rugged, simple switch mechanism capable of withstanding the rigors of railway service.

5 Other objects of the invention will become apparent from the specification and appended drawing in which

Fig. 1 is an elevation of the device;

Fig. 2 is a vertical section through the lower portion of the device;

Fig. 3 is a section through a lower portion of the lantern as indicated on the line 3—3 of Fig. 2;

Fig. 4 is a transverse section through the lantern as indicated on the line 4—4 of Fig. 2.

The lantern, generally indicated by 10, comprises a casing 11 having a handle 12 preferably made of some insulating material. The lantern is supported by the base 20 and guard ring 13 to which it is attached by the legs 14 which are welded or otherwise suitably affixed to a skirt 15 which telescopes for a short distance over the end of the casing 11. The skirt may be held to the casing 25 by the machine screws 16 or by other suitable means.

A flange 17 is turned inwardly at the end of the skirt and supports a reflector 18 and an insulating plate 19. Spacing studs, 21, 21 which may be molded integrally with the plate, hold it spaced apart from the end 22 of the casing 11. The battery 23 inside the casing has a lateral terminal 24 in contact with the end 22 and its central terminal 25 is in contact with an insulated stud 26. The stud is spaced apart from the casing by means of the insulating washers 27 and 28 and is headed over upon a spring contact strip 29, which extends laterally to bear against the 35 central terminal of two lamps 31, 31 maintained in the sockets 32, 32. These may be threaded metal inserts molded into the plate 19.

A metal strip 33 is crimped over a piece of 45 insulating material to form a shoe 34 which may slide in a limited arc along the inner wall of the skirt. A laterally extending handle 35 is threaded into the combined nut and contact element 36 and which moves in the 50 clearance slot 37 cut in the skirt 15.

Two spring elements 38, 38 have eyes or loops 39 formed in them which slide over the spacing studs 21, 21. Their ends 41, 41 are turned upwardly and bear against the shoe 34. The arms 42, 42 engage the sockets 55 32, 32 and preferably fit into retaining grooves 43, 43 cut around the sockets. The notches 40, 40 cooperating with the ends 41, 41 offer resistance to the movement of the shoe at the "off" and "on" points.

When the handle 35 is moved from side to side, the end of one spring will be brought into contact with the nut 36 and, consequently, a circuit will be established which may be traced through the spring 38 to the socket 65 32 through the lamp 31 and back to the battery. When the handle is pushed in the other direction, the other light is illuminated.

This simple, rugged, dirt-proof arrangement gives unfailing service under hard use. The specific embodiment herein shown for illustration may be changed as needs may require within the scope of the appended 75 claims.

I, therefore, claim as my invention:

1. An electric hand lantern comprising a battery casing having a permanently closed end, a skirt having its open end telescoped over the closed end of the casing and maintaining an insulating plate spaced from the casing, a shoe of insulating material mounted to slide against the inner wall of the skirt, a socket carried by the insulating plate, a lamp in the socket having its central contact in electrical communication with one pole of the battery, a spring pressed contact member bearing against the socket and the shoe and contacts on the shoe electrically connected to the opposite pole of the battery. 90

2. An electric lantern comprising a casing, a plate of insulating material spaced from the end of the casing, a socket carried by the plate, a lamp in the socket having its central terminal electrically connected to one pole of a battery in the casing, a skirt extending between the casing and the plate, a shoe of insulating material adapted to slide along the inner wall of the skirt and a spring contact member adapted to press outwardly upon 100

the shoe and against the socket, and to engage a contact upon the shoe when the shoe is rotated to an appropriate position.

3. An electric lantern comprising a casing, 5 a plate of insulating material spaced from the end of the casing, two sockets carried by the plate, lamps in the sockets having their central terminals electrically connected to one pole of a battery in the casing, a skirt 10 extending between the casing and the plate, a shoe of insulating material adapted to slide along the inner wall of the skirt and spring contact members adapted to press outwardly upon the shoe and against the sockets 15 and to engage contacts upon the shoe when the shoe is rotated to an appropriate position.

4. An electric lantern comprising a casing having a permanently closed end, a skirt 20 telescoping over the end of the casing and maintaining an insulating plate spaced therefrom, an insulated terminal in the end of the casing, a battery having its lateral contact electrically connected to the casing 25 and its central contact connected to the insulated terminal, a shoe bearing contacts in electrical connection with the lateral battery contact and adapted to slide along the inner wall of the skirt, a socket in the insulating 30 plate, and spring pressed elements bearing constantly against the shoe and the socket and electrically connecting the battery and the socket when the shoe is in the appropriate position.

5. In an electric lantern, a casing, a skirt telescoping over the casing and engaging the periphery of an insulating plate bearing a plurality of spacing studs, a socket in the plate, a slidable insulating shoe having a contact thereon electrically connected to the casing, and a spring member looped about a spacing stud and bearing upon the socket and the shoe to connect the socket to the casing when the shoe is in an appropriate position.

6. In an electric lantern, a casing, a skirt telescoping over the casing and engaging the periphery of an insulating plate bearing a plurality of spacing studs, two sockets in the plate, a slidable insulating shoe having contacts thereon electrically connected to the casing, two spring members looped about the spacing studs each bearing upon a socket and the shoe and which connect the socket to the casing when the shoe is in an appropriate position.

7. In an electric hand lantern, a casing, a plate of insulating material spaced from the casing and bearing a socket, a lamp in the socket, a central battery contact in electrical 60 connection with the base terminal of the lamp, a shoe of insulating material adapted to slide along the inner wall of the casing and having a button projecting through the casing, an electrical conductor extending between the shell contact of the lamp and the

shoe, and a piece of conductive material carried by the shoe and adapted to be connected to the lateral terminal of a battery, said material being adapted to be brought into and out of engagement with the electrical conductor upon movement of the shoe. 70

In testimony whereof I affix my signature.

CARL H. LARSON.
